Primary Examiner — Catherine S Posthauer(74) *Attorney, Agent, or Firm* — Quarles & Brady LLP(57) **CLAIM**

The ornamental design for a cap, as shown and described.

DESCRIPTION

FIG. 1 is an isometric front, top, and left side view of a cap, showing my new design; FIG. 2 is a front elevational view of the cap of FIG. 1; FIG. 3 is a rear elevational view of the cap of FIG. 1; FIG. 4 is a left side elevational view of the cap of FIG. 1; FIG. 5 is a right side elevational view of the cap of FIG. 1; FIG. 6 is a top plan view of the cap of FIG. 1; and, FIG. 7 is a bottom plan view of the cap of FIG. 1.

The evenly broken lines are shown for the purpose of illustrating parts of the article that form no part of the claimed design. The dot-dash lines represent the boundaries of the claim and form no part thereof.
